UNITED STATES PATENT OFFICE.

JAMES D. NELSON, OF CINCINNATI, OHIO.

ELECTRIC SIGNAL SYSTEM.

1,254,152.

Specification of Letters Patent. Patented Jan. 22, 1918.

Application filed February 26, 1917. Serial No. 150,895.

To all whom it may concern:

Be it known that I, JAMES D. NELSON, a citizen of the United States of America, and resident of Cincinnati, in the county of 5 Hamilton and State of Ohio, have invented a new and useful Improvement in Electric Signal Systems, of which the following is a specification.

In electric signal systems of the type 10 herein disclosed, and now in use, each kind of device to be supervised by the system, has controlling magnets, the resistance of which is at all times in the circuit of the system. This results in added resistance to 15 the circuit of the system, each time an additional device to be supervised, is added to the circuit. Eventually the circuit resistance is increased to such an extent by such additions that the number of devices which 20 can be installed on a single circuit, has to be limited, any more devices to be supervised therefore, necessitating the installation of another system. This entails an additional expense and care. Furthermore, 25 certain signal systems now employed, necessitate the use of a battery or other source of electric energy on the protected premises. This is also an added expense and requires constant attention. There is another 30 system in which mechanically actuated transmitters have been devised and which requires a transmitter for each device to be supervised, differing thereby from the two preceding systems which only require one 35 transmitter for each kind of device being supervised and therefore the third named system may become the most expensive to install and in the opinion of some has the disadvantage of requiring that transmitters 40 be installed at times in undesirable locations.

To overcome these objections to systems now in use I have devised the system now to be described and which I have disclosed 45 as being particularly adapted for use in the supervision of sprinkler systems.

An object of my invention is to produce a signal system in which the resistance of the controlling magnets of the device to be 50 supervised, is normally out of the circuit until momentarily introduced therein upon actuation of any one of the supervised devices.

A further object is to produce an im- 55 proved supervisory electric signal system of

the central energy type, in which the resistance of the circuit is not permanently increased either when the supervised devices are positioned at trouble or normally positioned.

60

A further object is to produce a supervisory electric signal system in which the number of devices which may be supervised, is unlimited.

These and other objects are attained in 65 the signal system described in the following specification and illustrated in accompanying drawings, in which;

Figure 1 is a diagrammatic view of a supervised device, the signaling apparatus 70 controlled by it, and the electrical connections thereof, together with a portion of the line circuit in which the signaling apparatus is located.

Fig. 2 is a simplified diagrammatic representation of the electric connections and switches disclosed in Fig. 1.

Fig. 3 is a diagrammatic representation of the complete supervising signal system embodying my invention, showing the central or signal receiving station and a series 80 of four signaling mechanisms, each controlled by two supervised devices.

In the illustrated embodiment of my im- 85 proved system I have shown a gate valve 4 as an example of device in a sprinkler system to be supervised by my improved signal system. An alarm or signal transmitter 5 is provided for responding to the movements of the valve when it is changed from 90 its normal wide open position to any position intermediate its open and closed positions.

Suitable electrical connections and switches to be hereinafter more fully described, are provided for co-operatively associating the device 4 and transmitter 5 together and with the main circuit. Diagrammatically I have shown the valve 4 as being 95 operatively connected with a switch 6, the device illustrated for such a purpose consisting of a bell crank lever 7 pivotally mounted on the valve at a point 8 and provided with a switch operating arm 9 and an arm 10 which carries a roller 11 adapted to engage a notch 12 in the stem 13 of the 105 valve.

Normally when the valve is wide open, the notch 12 registers with the roller 11 so that the lever 7 and switch 6 will remain in the normal positions disclosed in Fig. 1. As soon as the valve is moved to 110

close it, the notch is brought out of register with roller 11 to cause lever 7 to move to the dotted line position and consequently to shift switch 6 to the dotted line position.

5 Transmitter 5 consists of an operating electromagnet 14 adapted to operate an armature 15 when properly energized, the armature being connected with one arm 16 of a bell crank releasing lever 17. The other 10 arm 18 of lever 17 engages at its end an escapement pawl 19 adapted to control the movement of a train of gears 20, 21, 22, 23 and 24, gear 24 being provided with any suitable source of power not shown, for 15 actuating the train. Gears 22 and 23 are mounted upon a shaft 25 carrying a signal transmitting wheel 26 adapted to coöperate with a circuit breaker 27, the operating finger 28 of which bears upon signal wheel 26.

20 Mounted upon a shaft 29 carrying gear 24 is a releasing disk 30 having a series of notches 31 and another series of notches 32 for coöperation with a detent 33 formed on arm 18 of releasing lever 17. Adjacent to 25 disk 30 is a switch operating cam 34 adapted to control the movements of a switch 35, the operating arm 36 of which engages the surface of the cam in the same manner that arm 28 of the circuit breaker 27 engages 30 signal wheel 26.

Magnet 14 is of special construction, the center of its winding being connected with a lead 37 and its terminals being connected with leads 38 and 39. The purpose of such 35 a construction will be hereinafter more fully described.

Circuit breaker 27 consists of two fingers 40 and 41, which engage contacts 42 and 43 which when the fingers are in their normal 40 positions such as disclosed in Fig. 1, connect the apparatus above set forth, with the line circuit. In their opposite or dotted line positions, as disclosed in Fig. 1, the fingers engage contacts 44 and 45 which are grounded by means of a lead 46. Switch 35 consists of a series of fingers 47, 48, 49 and 50, fingers 47, 48 and 50 of which when in their normal 45 positions, engage contacts 51, 52 and 53 respectively, fingers 47, 49 and 50 being adapted to engage respective contacts 54, 55 and 56 when in their reversed or dotted line 50 positions as disclosed in Fig. 1. Contact 54 is grounded by means of a lead 57, the remaining contacts being connected with other portions of the apparatus as will be herein- 55 after more fully set forth.

Switch 6 which is directly controlled by operation of valve 40 consists of a series of fingers 58, 59 and 60, finger 58 being adapted 60 when in its normal position, to engage a contact 61, as disclosed in Fig. 1, fingers 59 and 60 being adapted to engage contacts 62 and 63 when in their reversed or dotted line positions, as disclosed in Fig. 1, contact 62 being 65 grounded by means of a lead 64, the remain-

ing contacts being suitably connected with the remaining portions of the apparatus as will be hereinafter more fully set forth.

Cam 34 is provided with a series of lobes 65 which are connected with a series of depressed or low portions 66 by means of inclines 67 at their forward ends and by means of sharp drops 68 at their rear ends. The positions of lobes 65 on cam 34, when detent 33 engages notches 31 of releasing wheel 30, 70 is such that the cam engaging end 69 of finger 36, is in the position disclosed in Fig. 1, ready to drop into the adjacent depression 66 as soon as the lever 17 is raised to withdraw its detent 33 from notch 31 to permit 75 shaft 29 to rotate in a counter clockwise direction as indicated by the arrow. In this normal position, the end 70 of finger 28, lies adjacent to one of the signal wheel teeth 71 of signal wheel 26, ready to send a signal as 80 soon as fingers 40 and 41 are lifted to break the circuit. Fingers 40 and 41 normally are connected into the main line circuit and form a portion thereof as will now be described. Finger 41 is connected to main line 72 and 85 its contact 43 is connected with contacts 53 and 55 of switch 35 by means of a connection 73, lead 39 of one terminal of releasing magnet 14 being connected therewith as shown. Contact 53 of switch 35 being normally engaged by finger 50 thereof, finger 50 necessarily forms a portion of the main line circuit and is provided with a connection 74 which connects it with contact 61 of finger 58. Finger 58 is also in normal engagement 90 with contact 61 and consequently forms a portion of the main line circuit when in this position. Therefore, it is provided with a connection 75 which connects it with finger 47 of switch 35, contact 51 of which is engaged normally by finger 47. For this reason finger 47, when in this position also forms a portion of the main line circuit. Contact 51 is provided with a lead 76 which connects it with a connection 77 extending 95 between finger 60 of switch 6 and contact 42 of circuit breaker 27, to both of which it is connected. Lead 76 and connection 77 also form a portion of the main line when the parts are in the position shown in Fig. 1. Lead 38 of the opposite terminal of releasing magnet 14 is connected with connection 77 as disclosed. Contact 42 of circuit breaker 27 being normally engaged by finger 40 thereof, finger 40 therefore forms a portion 100 of the main line circuit and is connected with the opposite portion 78 thereof as disclosed. It will be seen that by these connections the main line circuit is intact throughout the apparatus locally connected with the supervised device, and furthermore, it will be seen that operating magnet 14 is shunted by reason of the connections made through switches 6 and 35. Contacts 52 and 56 are connected by respective leads 79 and 80 with 105 110 115 120 125 130

central lead 37 of magnet 14, finger 49 of switch 35 and contact 63 of switch 6 are connected by means of lead 81, and finger 48 of switch 35 and finger 59 of switch 6 are connected by means of lead 82.

In Fig. 2, the magnet 14, circuit breaker 27, switch 35, switch 6, and the electrical connections between these elements, are disclosed, mechanical details of the apparatus disclosed in Fig. 1, being omitted for clearness of illustration. Corresponding connections and elements of the switches are designated by the same reference numerals as indicated by Fig. 1, and for this reason the path of the circuit for the changes of the positions of the switches, may if preferred, be more easily followed than by reference to the entire apparatus disclosed in Fig. 1.

In Fig. 3 I have shown in diagrammatic form the entire circuit, including that portion represented by the central station. The central station has been designated by the dot-dash line in this figure, all elements of the system located within this line being included in the central station equipment. At 83, 84, 85 and 86 I have shown diagrammatically the apparatus disclosed in Fig. 1, portions 87, 88, 89 and 90 representing those elements represented by the transmitter mechanism, the circuit breaker 27 and switch 35, the supervised devices 4 and the respective switches 6 being represented at 91, 92, 93, 94, 95, 96, 97 and 98. At the central station I have disclosed the source of energy as being a battery 99 suitably grounded at the point 100 and connected with the main line at its opposite terminals, signal recording devices 101 and 102 of the open circuit type also being disclosed, the signal responsive magnets 103 and 104 of which are directly connected into the main line for operating devices 101 and 102 respectively. Magnets 103 and 104 control respective armatures 105 and 106 which when brought to engage respective contacts 107 and 108, cause operation of the respective signal indicating devices 109 and 110. In the description of the operation as well as the illustration of my improved system, the circuit will be described as that of the closed circuit type, although the system is equally adapted for operation when of the open circuit type. Because of being shown and described as of the closed circuit type armatures 105 and 106 normally are lifted by magnets 103 and 104 from engagement with respective contacts 107 and 108. For this reason it is only when the circuit is broken that these armatures are released to permit the signal indicating devices 109 and 110 to record the signals sent by transmitter 5 in response to operation of the valve mechanism.

In operation the apparatus is in its normal condition as disclosed in Fig. 1, the elec-

trical connections of its operating switches and circuit breaker being as disclosed therein and in Fig. 2. In this condition the main line circuit is as follows, considering the energy as entering along main line 72 and 70 leaving the apparatus along main line 78 as indicated by the arrows. The path taken by the current is 72, 41, 43, 73, 53, 50, 74, 61, 58, 75, 47, 51, 76, 77, 42, 40 and thence out along the main line 78 to the central station, 75 through magnets 103 and 104 and the source of electrical energy 99 and back through main line 71. Should a series of supervised devices be connected in on the main line they may each be provided with a separate 80 transmitter 5, or several supervised devices may be connected with one transmitter and several such units inserted on the main line as disclosed at 87, 88, 89, and 90 in Fig. 3. Whether one or a series of apparatus such 85 as disclosed in Fig. 1, be connected into the main line, the path of the current when the devices are in their normal positions, will be the same as that disclosed in Fig. 1 and just described.

It will be assumed that valve 4 which is in its normal wide open position, is closed. This causes notch 12 to be brought out of register with roller 11 and through bell crank 7, to cause switch 6 to bring fingers 95 58, 59 and 60 thereof to the dotted line positions shown. The circuit is immediately broken at contact 61 and fingers 59 and 60 are brought into engagement with contacts 62 and 63 respectively. The result is that 100 the current entering through main line 72, takes the following path through 41, 43, 73, 39, one half of magnet 14, 37, 79, 52, 48, 82, 59, 62 and 64, at which point it is grounded, the current returning through ground connection 100 to the source of electric potential 99. The current passing through one half of magnet 14 is now sufficient to attract armature 15 and lift lever 17 to remove its detent 33 from notch 31 to release wheel 110 30 and simultaneously to release escapement pawl 19. The gear train of transmitter 5 immediately starts to operate and lobe 65 passes from beneath end 69 of finger 36 of switch 35. This permits end 69 of finger 36 115 to drop into depressed portion 66 of cam 34 so that switch fingers 47, 48, 49 and 50 may move to the dotted line positions disclosed in Fig. 1. Finger 47 disengages contact 51 and engages contact 54, finger 48 120 breaking the circuit through the magnet 14 by disengaging contact 52, finger 49 engaging contact 55 and finger 50 disengaging contact 53 and engaging contact 56. A new circuit is thus established as follows; 72, 41, 125 43, 73, 55, 49, 81, 63, 60, 77, 42, 40, and out over main line 78. With the parts in these positions, the transmitter mechanism operates to bring teeth 71 of signal wheel 26 into operative engagement with end 70 of circuit 130

breaker operating finger 28. This causes circuit breaker fingers 40, 41 to disengage contacts 42 and 43 and to break the circuit, being brought to their dotted line positions to engage contacts 44 and 45 so as to momentarily ground the circuit. This permits magnets 103 and 104 which have been energized, to release armatures 105 and 106 to close the local circuit through the signal indicators 109 and 110 located at the central office. This occurs as many times as there are teeth 71 to be brought into engagement with finger 28 to circuit breaker 27. Thus the trouble and alarm signal is transmitted to the central office. Upon completion of the signal, notch 32 having been brought into register with detent 33, lever 17 drops to stop operation of escapement pawl 19 since the circuit of magnet 14 was shunted when switch 35 was brought into operation.

As soon as the trouble indicated by the closing of the valve 4 has been removed by opening the valve, the notch 12 is brought into register with roller 11 to permit lever 7 to be restored to its normal position thus permitting switch fingers 58, 59 and 60 again to move to the full line positions indicated in Fig. 1. A new circuit is again established as follows: 72, 41, 43, 73, 39, 37, 80, 56, 50, 74, 61, 58, 75, 47, 54 and 57, at which point the circuit is grounded to return through ground 100 at the central station. This reestablishes the circuit through the transmitter releasing magnet 14 and again causes lever 17 to lift detent 33 so that notch 32 will be disengaged and so that pawl 19 will be released to permit operation of the transmitter. Upon completion of the trouble signal the cam 34 has been brought to such a position that end 69 of finger 36 occupies a point midway between shoulder 68 of lobe 65 and incline 67 of adjacent lobe 65. Detent 33 and arm 18 having released the transmitter train, teeth 112 of signal wheel 26 are brought into engagement with end 70 of circuit breaker operating finger 28 to again cause its operation. The transmitter now operates to bring the remaining portion of hollow 66 of cam 34 beneath end 69 of finger 36 and to bring the blank portion of signal wheel 26 beneath end 70 of circuit breaker operating finger 28. Just previous to the engagement of teeth 112 with end 70 of circuit breaker operating finger 28, end 69 of switch operating finger 36, is lifted by incline 67 to change the position of fingers 47, 48, 49 and 50 once more to the full line positions disclosed. The parts are now in the positions disclosed in full lines in Fig. 1 and the teeth 112 are in position to transmit the O. K. signal. Finger 36 having been lifted by incline 67 to bring it on to lobe 65, continued operation of the transmitter brings teeth 112 successively beneath finger 28 to cause operation of the cir-

cuit breaker to transmit the O. K. signal. The signal having been completed, the transmitter continues to run until the next notch 31 comes into registration with detent 33, at which time lever 17 drops and stops the transmitter train, the next series of trouble signals sending teeth 71, having been brought into position to transmit the next trouble signal immediately upon operation of the transmitter. The parts of the system upon stopping after having transmitted the O. K. signal, are left in the full line positions disclosed in Fig. 1.

It will be seen that introduction of the transmitter releasing magnet into the system, is had only for purposes of releasing the transmitter, the introduction being temporary and only of sufficient duration to lift lever 17 to release the transmitter train. For this reason, under normal conditions, the system is absolutely free of the resistance usually imposed upon it by the introduction of each of the operating magnets of the signal sending transmitters located in the system.

In addition to this, it will be seen that because the transmitter releasing magnets are normally out of the circuit, the number of devices to be supervised are practically unlimited. Another advantage attained by my improved system is that there is but a single source of electric potential which is located at the central or signal receiving station of the system, whereas with one of the old systems now in use a source of energy must be maintained at the central station, see Fig. 3, as well as at each place to be supervised, as at 87, 88, 89 and 90. In addition to this, the source of electric potential, because of the low resistance of the circuit, can be much less powerful than those employed in other central energy systems heretofore employed. Such a system as disclosed by me is therefore, much more cheaply installed and maintained than other systems, since not only the cost of apparatus is materially reduced, but also the cost of maintaining the systems in operative condition. Because of those advantages the system herein disclosed is of necessity much more reliable than other systems.

Having thus described my invention, what I claim is:

1. An electric signal system consisting of a signal responsive device, an electromagnetically released signal transmitter, a device to be supervised, a means adapted to introduce the transmitter magnet into the circuit to release the transmitter upon change of said device from one position to another or return to its normal condition, and means adapted to remove the magnet from the circuit upon initiation of operation of said transmitter.

2. An electric signal system consisting of

5 a signal responsive device, a transmitter, an electromagnet adapted to release the transmitter, a device to be supervised, and means controlled by the device, adapted to introduce the magnet momentarily into the circuit to release the transmitter upon change of said device from one position to another or return to its normal condition.

10 3. An electric signal system consisting of a signal responsive device, a transmitter, an electromagnet adapted to release the transmitter, a device to be supervised, a switch operatively connected with the device, adapted to introduce the magnet into the circuit instantly upon change of said device from one position to another or return to its normal condition, and a switch operatively connected with the transmitter, adapted to remove the magnet from the circuit instantly 15 upon initiation of operation of the transmitter.

15 4. An electric signal device comprising a signal responsive device, a signal transmitter, a device to be supervised, an electromagnet adapted to release the transmitter, and means operatively connected with the transmitter and the device, adapted normally to shunt said magnet and to remove the shunt upon change of said device from 20 one position to another or return to its normal condition and upon initiation of operation of said transmitter to restore said shunt.

25 5. An electric signal system comprising a signal responsive device, a signal transmitter, a circuit breaker operatively connected 30

40 with said transmitter, a device to be supervised, an electromagnet adapted to release the transmitter, and means operatively connected with the transmitter and the device to be supervised, adapted to introduce the magnet into the circuit upon change of said device from one position to another or return to its normal condition and to remove the magnet from the circuit upon initiation of operation of said transmitter, whereby 45 the circuit breaker may transmit signals in response to operation of said transmitter.

45 6. An electric signal system consisting of a signal responsive device, a signal transmitter, a circuit breaker responsive to operation of said transmitter, an electromagnet adapted to release the transmitter, a device to be supervised, a switch controlled by the device, adapted to introduce the magnet into the circuit upon change of said device from 50 or return to its normal condition, and a second switch operatively connected with the transmitter, adapted to remove the magnet from the circuit upon initiation of movement of said transmitter, whereby the transmitter upon initiation of operation, will operate the circuit breaker to transmit signals to said signal responsive device.

55 In testimony whereof, I have hereunto subscribed my name this 24th day of Feb- 60
ruary, 1917.

JAMES D. NELSON.
